UNITED STATES PATENT OFFICE.

GEORGE CLARK, OF MARINETTE, WISCONSIN.

STEAM-FEED WORKS FOR SAW-MILLS.

SPECIFICATION forming part of Letters Patent No. 275,800, dated April 17, 1883.

Application filed January 24, 1883. (No model.)

To all whom it may concern:

Be it known that I, GEORGE CLARK, a citizen of the United States, residing at Marinette, in the county of Marinette and State 5 of Wisconsin, have invented new and useful Steam-Feed Works for Saw-Mills, of which the following is a specification, reference being had to the accompanying drawings.

This invention relates to steam-feed works 10 for circular saw mills, and has for its object to provide a simple, efficient, and compact feed mechanism by which the saw-mill carriage can be fed and gigged at any required speed.

The invention consists, broadly, in a cylinder, 15 which is of a length much less (about one-fifth) than the length of travel of the carriage, arranged at one end of the mill. The piston of this comparatively-short cylinder turns alternately in both directions (so as to alternately 20 feed and gig the mill-carriage) a pulley that carries, in connection with another pulley at the other end of the mill, an endless metallic cable, to which the saw-mill carriage is secured. In this improved steam-feed the elasticity of 25 the steam and of the metallic cable or rope (which latter is preferably constructed of steel) combine to form a perfect cushion in starting and stopping, and affords instantaneous relief to the saw when entering hard lumber, knots, 30 bunches, and the like.

In the drawings, Figure 1 is a longitudinal elevation, with portions in section, of my improved feed-works, and showing the log-carriage in position. Fig. 2 is a plan view of the 35 same. Fig. 3 is an end view, looking toward the front of the saw.

Referring to the drawings, A designates the cylinder of my improved steam-feed works, which is preferably placed under the floor B 40 of the mill out of the way. In the cylinder A works an ordinary piston-head, C, and from each side of this piston-head extends a section of drive-chains, D D, which is connected to the piston-head, and is preferably formed of steel. 45 These flexible steel chains D D mesh with strong toothed wheels E E, that are inclosed in a steam-tight casing, F, at each end of the cylinder A. The toothed wheels E E are fixed on shafts G G', that pass through stuffing-boxes H H in the casings F F. There is one toothed wheel and its shaft at each end of the

cylinder, and one of the shafts, G', carries a fixed pulley or drum, I, as shown.

J J are tubular guides or chambers arranged on the cylinder, and serving to guide the free 55 ends of the flexible chains D D.

On corresponding ends of the shafts G G' are fixed pulleys K K, that carry a band, L, by means of which mechanism power from the shaft G, when the piston-head is operating to 60 turn the toothed wheel thereon, is transmitted to the shaft G' to turn the latter.

M N designate respectively the feed and exhaust ports of the rotary valve O, of the cylinder A, and P P are the pipes leading from 65 the said valve to each end of the said cylinder, through which steam is admitted to the latter. This rotary valve is operated by the sawyer or operator by means of a lever, Q, that is connected by a pivoted rod, R, with a band wheel 70 or pulley, S, around which passes a band, T, that is carried at its other end by another band wheel or pulley, U, on the key V of the said valve. This operating-lever Q can be handled with the greatest ease, and causes no tremor 75 or jar upon the sawyer's hand, the whole of this mechanism being very light. It is only necessary to throw the lever a short distance in either direction to operate the valve.

W designates the strong steel-wire cable or 80 rope that carries the log-carriage. This rope is wound a number of times around the pulley or drum I, and also passes once around a pulley, X, of less diameter than the pulley I, and arranged at the opposite end of the carriage- 85 way.

Y designates a tightener for the steel-wire drive-rope, which comprises a swinging frame, Z, carrying a pulley, A², over which the said rope travels, and provided with one or more 90 weights, B², arranged on a line, C², extending from the lower end of the pivoted or swinging frame up and over a pulley. These weights serve to hold the pulley of the tightening mechanism to the drive-rope. 95

D² designates a brake-wheel that is fixed to the shaft G nearest the sawyer, and is provided with a brake-band, E², that is connected to a lever, F², arranged to be depressed by a rod, G², which is operated by the foot of the 100 sawyer.

The pulleys I and X and the drive-rope that

they carry will project slightly above the mill-floor B. This projecting portion is protected by a boxing, H², having a longitudinal slot, I², in its top through which travels the clamp J², that is attached to the carriage and is secured to the drive-rope. At the point where the said standard clamps the drive-rope I propose to join the two ends of the latter.

The brake mechanism above described, being attached to the shaft G, acts directly upon the piston-head in the cylinder through the agency of the toothed wheel on the said shaft G, and the drive-chain in the cylinder that meshes with the latter. This brake is operated either by the foot of the sawyer or by steam-power, and is of such power that it gives the sawyer, in connection with the valve-governing lever, perfect control of the carriage.

This improved steam-feed works equally as well in any position, either horizontally or vertically, and is of especially simple and inexpensive construction. The motion of the piston-head is transmitted directly to the shaft G', carrying the main drum or pulley I, by means of the drive-chains in the cylinder and the toothed wheels. As the pulley I revolves the steel-wire rope or cable travels in the direction that the said pulley is turning and carries the carriage.

From the directness with which the power is transmitted from the piston-head to the main drum or pulley I, and the frictionless nature of the mechanism, a comparatively small piston and cylinder suffices, and but little steam is required to work the feed-works.

I claim as my invention—

1. An improved feed-works for circular saw mills, comprising a cylinder arranged at one end of the carriage-way, a drum or pulley adjacent thereto and acted upon by the piston of the said cylinder so as to be turned alternately in both directions, a pulley journaled at the other end of the carriage-way, and a cable or rope passing over the said pulleys and secured to the log-carriage, as set forth.

2. The combination of a cylinder having toothed wheels fixed on shafts journaled at each end, a piston working therein, drive-chains secured to the piston and extending from both sides thereof and engaging the toothed wheels to turn the same, pulleys fixed on the shafts of the toothed wheels outside the cylinder and connected by a belt or other means, and a drum or pulley fixed to the shaft of one of the toothed wheels and carrying, in connection with another pulley at the other end of the carriage-way, a cable or rope to which the log-carriage is secured, as set forth.

3. As an improvement in saw-mill feed-

works, the combination of a cylinder carrying toothed wheels fixed on shafts projecting from the ends of the cylinder, a piston working in the cylinder, a section of drive-chain extending from the piston and engaging the toothed wheels to turn the shafts of the latter from a pulley or drum arranged on one of the shafts of the toothed wheels, and a cable connected with the said drum and with the saw-mill carriage, as set forth.

4. As an improvement in saw-mill feed-works, the combination of the cylinder having steam-ports and provided with auxiliary casings at its ends, toothed wheels turning in the said casings and fixed on shafts projecting therefrom, a piston working in the cylinder, drive-chains secured to the piston and extending from both sides thereof and engaging the toothed wheels, tubular guides or chambers arranged on the cylinder and serving to guide the free ends of the sections of drive-chain, a drum or pulley fixed on one of the shafts of the toothed wheels, and a cable passing around the said drum and secured to the saw-mill carriage, as set forth.

5. As an improvement in feed mechanism for saw-mills, the combination of a cylinder having toothed wheels fixed on shafts projecting at its ends, a piston working in said cylinder, sections of drive-chains secured to the piston and extending from both sides thereof and engaging the toothed wheels, pulleys fixed to the toothed wheels, shafts outside the cylinder and connected by a belt or other means, and a drum or pulley arranged on one of the toothed wheel shafts, and a cable passing around the pulley and connected to the saw-mill carriage, as set forth.

6. The combination, in saw-mill feed-works, with a cylinder provided with connecting mechanism by which it operates to feed the carriage, and having toothed wheels at its ends that are fixed on projecting shafts and are adapted to be operated by sections of drive-chain extending from the piston, the cable by which the carriage is reciprocated being secured to the carriage and arranged around a pulley or drum on one of the shafts of the toothed wheels, of a brake-wheel fixed on one of the shafts of the toothed wheels and provided with a brake-band that is connected to an operating-lever, as set forth.

In testimony that I claim the foregoing as my own I have hereto affixed my signature in presence of two witnesses.

GEORGE CLARK.
